(57) **CLAIM**

We claim the ornamental design for a torch having a pivotable top cover and folding blades, as shown and described.

DESCRIPTION

FIG. 1 is a top, front, and left side perspective view of the torch having a pivotable top cover and folding blades, wherein the pivotable top cover is disposed in a first position that covers a top end of the torch;

FIG. 2 is a bottom perspective view thereof;

FIG. 3 is a left side elevational view thereof;

FIG. 4 is a right side elevational view thereof;

FIG. 5 is a top plan view thereof;

FIG. 6 is a front side elevational view thereof;

FIG. 7 is a back side elevational view thereof;

FIG. 8 is bottom plan view thereof;

FIG. 9 is a top, front, and left side perspective view of the torch, with the pivotable top cover having been pivoted to a second position that uncovers the top end of the torch;

FIG. 10 is a bottom perspective view of the torch of FIG. 9;

FIG. 11 is a left side elevational view of the torch of FIG. 9;

FIG. 12 is a right side elevational view of the torch of FIG. 9;

FIG. 13 is a front side elevational view of the torch of FIG. 9;

FIG. 14 is a back side elevational view of the torch of FIG. 9;

FIG. 15 is a top plan view of the torch of FIG. 9; and,

FIG. 16 is a bottom plan view of the torch of FIG. 9.
The broken lines in the drawings depict portions of the torch having a pivotable top cover and folding blades which form no part of the claimed design.
